(57) **CLAIM**

The ornamental design for a baby bottle holder for feeding a baby, as shown and described.

DESCRIPTION

FIG. 1 is a perspective view of a baby bottle holder for feeding a baby, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof; and,

FIG. 8 is a perspective view thereof.

The broken lines illustrate portions of the baby bottle holder for feeding a baby that form no part of the claimed design.

1 Claim, 7 Drawing Sheets
